CLAIM

The ornamental design for a portable chair, as shown and described.

DESCRIPTION

FIG. 1 is a top, front, right perspective view of a portable chair showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a folded front view of an alternative claimed configuration of a portable chair showing our new design thereof;

FIG. 9 is a folded back view thereof; and,

FIG. 10 is a folded left side view thereof.

The broken line shown are included is for the purpose of illustrating portions of the portable chair and forms no part of the claimed design.

1 Claim, 10 Drawing Sheets
